CLAIM

What is claimed is the ornamental design for a stringed musical instrument bridge, as shown and described.

DESCRIPTION

FIG. 1 is a perspective view of the front of the stringed musical instrument bridge;

FIG. 2 is a front view of the stringed musical instrument bridge;

FIG. 3 is a back view of the stringed musical instrument bridge;

FIG. 4 is a left side view of the stringed musical instrument bridge;

FIG. 5 is a right side view of the stringed musical instrument bridge;

FIG. 6 is a top view of the stringed musical instrument bridge;

FIG. 7 is a bottom view of the stringed musical instrument bridge; and,

FIG. 8 is an alternative perspective view of the front of the stringed musical instrument bridge shown with environmental features depicted in broken lines forming no part of the claimed design.

The broken lines, where present, in the FIGS. illustrate environment of the stringed musical instrument bridge that forms no part of the claimed design.
